UNITED STATES PATENT OFFICE.

CHARLES C. WIENTGE, OF PROVIDENCE, RHODE ISLAND, ASSIGNOR TO THE HOWARD STERLING COMPANY, OF SAME PLACE.

DESIGN FOR A BACK FOR TOILET BRUSHES.

SPECIFICATION forming part of Design No. 22,355, dated April 18, 1893.

Application filed February 8, 1893. Serial No. 461,522. Term of patent 7 years.

To all whom it may concern:

Be it known that I, CHARLES C. WIENTGE, of Providence, in the county of Providence and State of Rhode Island, have invented and produced a new and original Design for the Backs of Toilet Brushes, &c., of which the following is a specification, reference being had to the accompanying drawings, forming part thereof.

10 Figure 1 of the drawings represents the back of a toilet brush illustrating my new design. Fig. 2 represents a cross-sectional view of the same on line $x-x$ of Fig. 1.

The leading features of my design for the 15 backs of toilet brushes, &c., consist in the symmetrical outline of the convex-back with a victor's wreath raised from the central portion thereof in bold relief.

No. 2 in the drawings indicates the convex-

back of a brush. Raised in bold relief from 20 this convex-surface is a wreath formed by a combination of the graduated clusters 3—3 of simulated laurel leaves interspersed with the berries 4—4 and joined together at the junction of two of these clusters by the representation of a ribbon which has the loops 5—5 extending within the wreath and the flowing-ends 7 and 8 depending from the wreath.

What I claim is—

The design for backs of toilet brushes, &c., 30 as herein shown and described.

In witness whereof I have hereunto set my hand.

CHARLES C. WIENTGE.
